UNITED STATES PATENT OFFICE.

HENRY H. HOSKINS, OF NORCATUR, KANSAS.

PRINTING-PRESS.

SPECIFICATION forming part of Letters Patent No. 630,701, dated August 8, 1899.

Application filed January 20, 1898. Serial No. 667,304. (No model.)

To all whom it may concern:

Be it known that I, HENRY H. HOSKINS, a citizen of the United States, residing at Norcatur, in the county of Decatur and State of 5 Kansas, have invented a new and useful Printing-Press, of which the following is a specification.

This invention relates to printing-presses of the variety comprising a bed for supporting the type-forms and an impression-cylinder adapted to roll over the type-form and carry the sheet to be printed. The improvement is directed to the aforesaid class of printing-presses, which are chiefly designed 10 to be operated by hand; but the novel features may be embodied in cylinder-presses 15 operated by steam or other power.

One of the chief objects in view is to lessen the labor usually required for operating a 20 press of given capacity and to enable a superior quality of work to be accomplished.

A further purpose of the improvement is to enable the operator to work the press with as little effort as possible and have the hands 25 free for feeding the sheets to be printed to the impression-cylinder, the latter being started on its return travel in either direction by a rebounding action, which is assisted by gravitational force to cause the cylinder to return after 30 a sheet has been printed and delivered upon the receiving-table.

Various other objects and advantages are contemplated and will suggest themselves to those skilled in the art as the details of the 35 organized structure are disclosed, and for a full understanding of the merits and advantages of the invention reference is to be had to the accompanying drawings and the following description.

40 The improvement is susceptible of various changes in the form, proportion, and the minor details of construction without departing from the principle or sacrificing any of the advantages thereof, and to a full disclosure of the invention an adaptation thereof is shown 45 in the accompanying drawings, in which—

Figure 1 is a perspective view of a hand cylinder-press embodying the essential features of this invention. Fig. 2 is an elevation 50 as seen from the remote side of Fig. 1. Fig. 3 is a longitudinal section, the dotted lines showing the lifting-tracks elevated.

Fig. 4 is a detail view showing the relation of the parts when the impression-cylinder is about at the limit of its return travel. Fig. 55 5 is a detail view showing the disposition of the parts when the impression-cylinder is about at the limit of its forward or outward travel. Fig. 6 is a detail view in plan elevation. Fig. 7 is a detail section of a side portion of the press, showing more clearly the means for adjusting the type-bed and preventing lateral and longitudinal displacement thereof.

Corresponding and like parts are referred 60 to in the following description and indicated in all the views of the drawings by the same reference characters.

The framework of the press comprises longitudinal tracks 1, uprights 2, and suitable 70 cross-bars connecting the tracks and uprights, so as to provide a substantial and rigid structure. In the event of the longitudinal tracks 1 being wooden sills they will be faced by iron or steel bars, which will resist the wear incident to the traveling thereon of the impression-cylinder. The middle portions of the 75 tracks are straight, and their end portions are straight and in a higher plane, and the parts intermediate of the middle and end portions 80 are inclined upwardly and outwardly to provide a gradual ascent and descent of the impression-cylinder when approaching or leaving the elevated end portions of the tracks. Brackets 3 rise above the rear ends of the 85 tracks 1 and have springs or buffers 4 in their front edges for the impression-cylinder to impact against, thereby gradually checking its forward movement and assisting materially in starting the impression-cylinder on its return travel toward the front end of the press.

Brackets 5 are located at the front ends of the tracks 1 and project above the same and have springs or buffers 6 at their inner edges for a purpose similar to the springs or buffers 4, and the feed-table 7 is secured to the upper 90 ends of the brackets 5. The table 8 for receiving the sheets when printed is located at the rear end of the press, and the ink-table 9 is arranged at the front end, both tables coming 95 between the end portions of the tracks 1 and supported upon cross-bars of the framework.

Similar rack-bars 10 are adjustably connected with the tracks 1 and are arranged ex-

terior thereto and are formed with vertical slots 11, through which bolts or machine-screws 12 pass for securing the rack-bars in an adjusted position. The toothed edge of each rack-bar conforms to the upper surface of the tracks 1, thereby enabling the gear-wheels or cog-gearing at the ends of the impression-cylinder maintaining a uniform meshing relation with the rack-bars at every point in the length of its travel.

The type-bed 13 is adjustable vertically to provide for a proper adjustment between the type-surfaces and the surface of the impression-cylinder. Any suitable means may be employed for adjusting the type-bed and holding it in an adjusted position, and, as shown, set-screws 14, mounted in threaded openings of cross-bars of the frame, have their upper ends in contact with the lower side thereof. Pins 15 between the said type-bed and the cross-bars of the frame retain the bed in position against lateral and longitudinal movement.

The impression-cylinder 16, of iron or other suitable material, is provided at its ends with cog-gearing 17 to intermesh with the teeth of the rack-bars 10 and has end hand-wheels 18, by means of which the cylinder is rotated when in operation. A longitudinal depression 19 is formed in a side of the impression-cylinder and receives the rod or shaft 20, provided with the grippers 21, which take hold of the advancing edge of the sheet to be printed, so as to carry it forward when the cylinder is passing over the type-forms. One end of the rod 20 extends through one end of the impression-cylinder and between two of the teeth of the adjacent gear-wheel and is bent, as shown at 22, and is adapted to engage with a trip 23 at the rear end of the press, so as to turn the rod and release the grippers, and to engage with a corresponding trip 24 at the front end of the press to operate the rod 20 and close the grippers upon the sheet to be printed. The rear trip 23 is disposed so as to release the grippers when the impression-cylinder is reaching the end of its forward travel, thereby permitting the printed sheet to be deposited upon the receiving-table 8. The front trip 24 is arranged to engage with the part 22 and close the grippers upon the advancing edge of the sheet as the impression-cylinder is completing its return travel.

The carriage for the inking-rollers 25 consists of a transverse rod or bar 26 and end bars 27, the latter having loose connection with the rod or bar 26, so as to admit of them and the inking-rollers having free vertical play independently of the rod or bar 26. The inking-rollers are of a length to come within the inner sides of the longitudinal tracks 1, whereas the rod or bar 26 extends slightly beyond the outer sides of the rack-bars 10 and have loose connection with journals of the impression-cylinder by means of links 28, having one end firmly attached to the rod 26 and the other end formed into a ring or bear-

ing to receive the journals of the impression-cylinder.

Elevating-tracks 29 are located on the inner sides of the tracks 1 and are adapted to have a limited vertical movement and are held in place by headed pins or fastenings 30, passing through vertical slots 31 of the said tracks. The tracks 29 rest upon the end portions of rods or shafts 32 near the ends of the press and which have eccentric or cam portions 33, upon which the tracks 29 directly rest, so as to be moved up and down at the proper time to effect the desired end. Arms 34 are dependent from the rods or shafts 32 and are connected by a rod 35, whereby the two shafts 32 move in harmony, so as to raise and lower both ends of the tracks 29 alike. An arm 36 is applied to an end of the rear rod or shaft 32 and is adapted to be engaged by the impression-cylinder when nearing the limit of its rearward travel, so as to turn the shafts 32 and cause the tracks 29 to rise, thereby holding the impression-cylinder away from the type-surfaces when returning to the front end of the press. An arm 37 is provided at one end of the front rod or shaft 32 and is engaged by the impression-cylinder when the latter is finishing its return or forward travel, so as to actuate the shafts 32 and cause the tracks 29 to lower, thereby permitting the inking-rollers and impression-cylinder to engage with the type-surfaces when moving forward or toward the rear end of the press.

Plates 38 are secured to the rear or delivery end of the feed-table 7 and project a short distance therefrom, so as to give proper support to the advancing end of the sheet and properly position it upon the impression-cylinder to insure the grippers taking a firm hold thereof. A rod 39 extends over the rear or delivery end of the feed-table 7 and has its end portions bent, as shown at 40, and pivotally connected with the feed-table, and one of the bent ends is extended, forming an arm 41, which is curved slightly in its length and adapted to be engaged by the impression-cylinder to effect a movement of the rod 39, so as to release the sheet next to be fed forward to be printed. Plates 42 are firmly attached at their upper ends to the horizontal portion of the rod 39 and their lower ends engage with the feed-table and constitute gages to limit the forward movement of the sheet to be printed until the impression-cylinder is in proper position to receive the advancing end of the said sheet, when the said cylinder will engage with the arm 41 and move the rod 39 and lift the plates 42 a sufficient distance to permit the sheet to pass by them to the impression-cylinder, when the grippers will take hold of the front end in a manner well understood in the art.

During the interval of the travel of the impression-cylinder from the feed-table and back thereto the plates 42 have their lower ends resting upon the feed-table, so as to hold in check the sheet placed in position upon the

table to be fed forward. Upon the return of the impression-cylinder to a starting position it will engage with the arm 41 and ride thereunder, thereby lifting the outer or free end 5 of the arm 41 and rocking the rod 39 upon the pivotal connection of its bent ends 40 with the feed-table. The rocking of the rod 39 throws the lower ends of the plates 42, rigidly attached thereto, rearwardly and upwardly, so as to admit of the passage of the sheet below the plates 42 to the impression-cylinder, when its advancing edge will be taken hold of by the grippers 21 in the manner herein set forth and well understood.

15 The press is operated in the following manner: The impression-cylinder and inking-rollers being at the front end of the press and upon the front elevated or raised portions of the tracks 1, the operator grasps one or both 20 of the hand-wheels 18 and starts the impression-cylinder toward the rear of the press. The forward inclined portions of the tracks 1 assist materially in urging the impression-cylinder forward, the impetus being sufficient 25 to cause the impression-cylinder to ride upon the rear inclined portions of the tracks 1 and engage with the springs or buffers 4, which latter gradually check the rearward travel of the cylinder and give an initial impetus 30 thereto on the return travel. During the forward and rearward travel of the cylinder the type-forms are inked by the inking-rollers traveling thereover, and as the cylinder reaches its rearward travel it engages with 35 the arm 36 and elevates the tracks 29 in the manner described at length herein, so that upon the return travel of the cylinder it will be held away from the type-surface, and as the cylinder approaches the limit of its return 40 travel it will engage with the front arm 37 and cause a lowering of the tracks 29, and the sheet to be printed will be fed forward and taken hold of by the grippers 21 in the manner set forth. The end portions of the 45 impression-cylinder will strike against the front springs or buffers 6, which will check its return and assist in again starting the cylinder on its forward travel toward the rear end of the press. In order that the impression-cylinder may receive a sufficient impulse 50 to carry it to the rear end of the press, the following means have been devised, and consist of a treadle 43, located within convenient reach of the feeder's foot, so as to be pressed 55 upon, and an impulse-lever 44, connected with the treadle by a rod 45 and having its active end projecting across the path of a pin 46, (see Fig. 6,) applied to the rim of the hand-wheel of the impression-cylinder adjacent to 60 the said impulse-lever, whereby movement is imparted to the said impression-cylinder upon pressing down upon the treadle 43. By this means the impression-cylinder receives an impulse without requiring the feeder or operator to apply the hands thereto and leaving 65 them free to properly feed the press.

Having thus described the invention, what

is claimed, and desired to be secured by Letters Patent, is—

1. In a cylinder printing-press, the combination with the impression-cylinder, and a pin applied to and projecting horizontally and eccentrically with reference to the said impression-cylinder, of a lever disposed to have the said pin project across the path of an end 75 portion thereof, substantially as and for the purpose described.

2. In a cylinder printing-press, the combination with the impression-cylinder having an end hand-wheel, and a pin projecting laterally from the hand-wheel and having an eccentric arrangement with reference thereto, of a lever having an end portion disposed to project across the path of the said pin, a treadle, and means connecting the treadle with 85 the said lever, substantially as and for the purposes specified.

3. In a cylinder printing-press, the combination of a frame provided with rack-bars, an impression-cylinder provided with gear-wheels meshing with the rack-bars, the rod 20 mounted in a recess of the impression-cylinder and extending through one end thereof and having one end arranged in the space between two of the teeth of the adjacent gear-wheel and bent at an angle, the grippers mounted on the rod 20 and adapted to engage a sheet of paper, a fixed vertical trip located near one end of the frame and arranged to engage the bent end of the rod, and a fixed horizontal trip located at the other end of the frame and arranged to engage the said bent end of the rod 20, to operate the grippers, substantially as described.

4. In a cylinder printing-press, the combination of fixed longitudinal tracks, movable tracks placed along the inner sides of the fixed tracks, positive connections between the fixed and movable tracks for guiding the latter in their vertical movements, an impression-cylinder mounted to travel upon the fixed tracks, an inking mechanism mounted to travel solely upon the movable tracks and receiving motion directly from the impression-cylinder, and means controlled by the impression-cylinder to raise and lower the movable tracks, substantially in the manner set forth and for the purpose described.

5. In a cylinder printing-press, the combination of fixed longitudinal tracks having upwardly-inclined end portions, movable tracks placed along the inner sides of the fixed tracks and having their tread-surfices straight throughout their length and passing by the inclined end portions of the fixed tracks, an impression-cylinder mounted to travel upon the fixed tracks, an inking mechanism mounted to travel solely upon the movable tracks and receiving motion directly from the impression-cylinder, and means controlled by the impression-cylinder to raise and lower the movable tracks, substantially as and for the purpose specified.

6. In a cylinder printing-press, the combi-

nation of fixed longitudinal tracks, movable tracks placed along the inner side of the fixed tracks, positive connections between the fixed and movable tracks for directing the latter in
5 their vertical movements, transverse shafts journaled at their ends to the fixed tracks and having cam portions upon which the movable tracks rest, arms pendent from said shafts and connected to cause a simultaneous
10 turning of said shafts in their bearings, an impression-cylinder mounted to travel upon the fixed tracks, an inking mechanism mounted upon the movable tracks and having con-

nection with the impression-cylinder to move therewith, and arms applied to an end portion of the aforesaid transverse shafts and projecting across the path of the impression-cylinder to be engaged thereby, substantially as set forth.

In testimony that I claim the foregoing as 20 my own I have hereto affixed my signature in the presence of two witnesses.

HENRY H. HOSKINS.
